UNITED STATES PATENT OFFICE.

PHIL L. ADAMS, OF STAPLES, MINNESOTA.

TARGET-TRAP.

1,178,371.

Specification of Letters Patent.

Patented Apr. 4, 1916.

Application filed July 24, 1914. Serial No. 852,964.

To all whom it may concern:

Be it known that I, PHIL L. ADAMS, a citizen of the United States, residing at Staples, in the county of Todd and State of Minnesota, have invented new and useful Improvements in Target-Traps, of which the following is a specification.

This invention relates to pigeon traps and more particularly to the carrier arm therefor.

In all clay pigeon traps it is essential that they be adapted to discharge the target at varying horizontal angles as well as vertical angles combined with the horizontal angles and also that the target be caused to rotate during its flight, otherwise an extremely wobbly motion and short and slow flight is obtained.

It is therefore the object of this invention to provide a combined throwing and carrier arm from which the pigeons can be thrown at varying horizontal angles and given a proper degree of rotation so that the target will sail directly.

It is another object of the invention to provide a combined throwing and carrier arm for clay targets in which the angle of flight is determined by the position of the target in the carrier.

Further objects will appear as the following specific description is read in connection with the accompanying drawing which forms a part of this invention, and in which:

Figure 1 is an elevation showing the combined throwing and carrying arm mounted upon a conventional representation of a pigeon trap, Fig. 2 is a perspective view of the arm, Fig. 3 is a top plan view of the arm with the upper flange broken away, and Fig. 4 is a transverse sectional view taken through the arm approximately on the line 4-4 of Fig. 3.

Referring more particularly to the drawing, 1 represents a support of any suitable character which has mounted thereon a standard 2 carrying the supporting bar 3. This supporting bar in practice is preferably constructed so as to have movement horizontally and vertically so as to vary the angular flight of the target although it may be constructed so as to move vertically only, the throwing arm to be hereinafter described taking care of the horizontal angle.

Passing through the outer end of the arm 3 is a stub shaft 4 having a crank arm 5 se-

cured to its lower end as shown. This crank arm is connected to one end of a spiral spring 6, the opposite end of the spring being connected to the standard 2 as shown at 7, and this latter connection is preferably an adjustable one so as to control the tension of the spring 6. The upper end of the stub shaft 4 is secured in the head 8 of the combined throwing arm and carrier so that upon rotation of the crank 5 by the spring, the carrier will be thrown from right to left discharging its target as will be hereinafter described.

The arm comprises a back plate 9 which is formed integrally with the head 8 and carries a friction strip 10 upon which the edge of the target 11 bears. This strip may be of any suitable construction or material, but I prefer to use a strip of rubber transversely corrugated as shown in Fig. 3. Secured to the upper and lower edges of the back plate 9 are supporting and guiding flanges 12 and 13, both of which increase in width from their inner to their outer ends as shown and each have heads 14 corresponding to the head 8 and apertured to receive the stub shaft 4.

As shown in Fig. 4, the supporting flange 12 is provided with a recess 15 upon its underside adapted to be engaged by a latching pin 16 controlled in any suitable manner and preferably being spring elevated so as to automatically engage in the recess when the arm is attracted.

In the operation of the device the arm or carrier is turned about upon its pivotal point until the latch and pin 16 engages in the recess 15 in the bottom of the arm. The target is then placed in the arm resting upon the flange 12 and having its edge in engagement with the corrugated friction base 10. When the latch and pin is released from the recess the arm will be forcibly rotated by the action of the spring 6 and the target will be ejected radially at different angles depending upon the position it occupies initially in the arm. For instance, if the target is placed at the point marked L it will remain within the arm throughout the full sweep and a left hand angle will be obtained. If the target is placed in the position indicated by the letter S it will be ejected and a straight away flight will be obtained while if it is placed in the arm at the position indicated by the letter R a right hand angle will be thrown. In either

instance, the target of course rests upon the flange 12 and has its edge in engagement with the friction piece 10. The flange 13 is constructed to prevent any wabbling of 5 the target although it normally does not engage the same.

Having thus described the invention, what I claim is:

A combined throwing arm and target carrier for pigeon traps comprising a pivoting head, a pair of parallel flanges integral with the pivoting head and gradually increasing in width from the head to their outer ends,

an edge engaging member connecting said flanges and holding them in parallel relation 15 and a corrugated frictional strip secured to said edge engaging member, the lower flange forming a supporting flange and the upper flange preventing displacement of the target.

In testimony whereof I affix my signature 20 in presence of two witnesses.

PHIL L. ADAMS.
